UNITED STATES PATENT OFFICE.

JAMES U. DUFFY, OF CLEVELAND, OHIO.

CAR-STOP.

1,379,398.

Specification of Letters Patent. Patented May 24, 1921.

Application filed October 10, 1919. Serial No. 329,724.

To all whom it may concern:

Be it known that I, JAMES U. DUFFY, a citizen of the United States, and a resident of Cleveland, county of Cuyahoga, and 5 State of Ohio, have invented a new and useful Improvement in Car-Stops, of which the following is a specification, the principle of the invention being herein explained and the best mode in which I have contemplated 10 applying that principle, so as to distinguish it from other inventions.

The present invention relates to a stop for cars which may be secured along a section of track to act as a stop or bumper of 15 the type shown in U. S. Letters Patent No. 1,276,023, dated August 20, 1918, granted to Edward W. Breyley and myself. A shoe or skid is provided for receiving the car wheel which is then adapted to slide along 20 with the shoe until it reaches a permanent stop fastened to the rail, the sliding action of the shoe being adapted to retard the movement of the car, so that it will be nearly stopped when the permanent stop block is 25 reached. The device is so arranged that the shoe will be returned to its forward position as the car is moved out of the device, and there are also means employed for releasing the car wheel from the shoe when the shoe 30 reaches its forward position. To the accomplishment of the foregoing and related ends, said invention, then, consists of the means hereinafter fully described and particularly pointed out in the claims.

35 The annexed drawing and the following description set forth in detail certain mechanism embodying the invention, such disclosed means constituting, however, but one of various mechanical forms in which the 40 principle of the invention may be used.

In said annexed drawing:—

Figure 1 is a side elevation of my stop showing shoe in its forward position adapted to receive the car wheel; Fig. 2 is a side 45 elevation showing the stop with a car wheel in place in an intermediate position along the rail; Fig. 3 is a side elevation showing the shoe in its final position against the permanent stop; Fig. 4 is a section through 50 the rail and channel iron on the line 4—4, Fig. 1; Fig. 5 is a section on the line 5—5, Fig. 2; Fig. 6 is a section on the line 6—6, Fig. 3; and Fig. 7 is a view similar to Fig. 2 showing a modified form of stop.

55 The present device is adapted to be mounted upon a rail 1, it being understood

that the devices are generally used in pairs, although only one device and rail are illustrated in the drawings. The mechanism consists of a permanent stop block 2 composed of two sections 3 having enlarged lower portions 4 adapted to fit below the ball of the rail, and secured thereto by means of bolts 5 which pass through the sections and the rail. As shown these sections extend upwardly beyond the ball of the rail and have their forward faces 6 inclined at an angle to the vertical.

Upon the rail in front of the permanent stop is mounted a channel iron 7 having an 70 upturned lug 8 at its rear end and a raised portion 9 at its forward end which inclines toward the rail surface.

Upon the channel iron is mounted a slide- 75 able skid or shoe 10 which has inclined forward portion 11 up which the car wheel is adapted to run, and is then provided with a curved portion 15 adapted to receive the car wheel therein. This shoe or skid has a number of depending legs which fit 80 over the channel iron and under the ball of the rail to hold the skid in place thereon. The rear leg 12 has its rear face inclined at the same angle as the forward face of the permanent stop with which it is adapted 85 to engage. The forward leg 18 on the skid is inclined in the opposite direction and is adapted to engage with a small permanent stop 14 mounted on the rail at the point ahead of the rail stop at which the device 90 is to be nominally set. The intermediate forward stop consists of two sections having heavy base portions 16 adapted to fit under the ball of the rail and provided with inclined side portions 17 which reach up- 95 wardly along the sides of the rail to approximately the top of the same, these sections being spaced from the rail sufficiently to allow the flange of the wheel to pass between the sections of the stop.

100 In Fig. 7 a modified form of shoe is shown, in which the shoe 20 has an inclined forward portion 21 having a curved rear side 23 and a curved rear portion 24, the shoe being large enough to receive both 105 wheels 25 and 26 of a car truck and hold them between the portions 23 and 24. In this form the channel 27 is of sufficient length to receive the forward truck and wheels 28 of the car so that the entire car is 110 removed from the rail itself and rides on the shoe and channel. The operation of this

form is similar to that shown in the other figures except that here the entire car is received on the device instead of a single truck.

The device is adapted to be placed in position upon a rail before the rail is placed upon the ties, but the shoe may be made removable as shown in our Patent No. 1,276,023 before mentioned. The normal receiving position of the stop is shown in Fig. 1 with the end of the shoe against the raised portion 9 of the channel iron and the forward leg of the shoe in contact with the forward rail stop. When a car wheel or truck is run into the shoe the momentum of the car is first adapted to slide the shoe backward along the channel section until the rear end of the shoe engages the upturned lug 8 upon the channel iron, at which time the device will be in the position shown in Fig. 2. The shoe and channel iron then slide together rearwardly until the shoe is in the position shown in Fig. 3, at which time the rear legs 12 on the shoe contact with the permanent stop block on the rail to stop the car. It will be seen that the forward wheel of the truck or the forward truck rides upon the channel iron and adds its weight upon the same to increase the friction between the channel iron and the rail, thus aiding in slowing down the speed of the car.

When the car is moved away from the permanent stop the shoe is pulled along upon the channel section until the forward wheel of the truck or the forward truck rides off on the section and the point of the shoe engages the raised forward end of the channel iron. The shoe and channel iron will then be moved forwardly together until the shoe contacts with the forward stop block which prevents the shoe from further forward movement and allows the car wheel or truck to be withdrawn from the shoe.

It is understood that the channel iron, as shown in Figs. 1 to 3 will be long enough to receive at least the full truck of a car whether the truck has the usual two wheels to the side or three wheels as in the usual Pullman cars, while in the form shown in Fig. 7 the channel will be long enough to receive the entire car. The distance between the forward and rear stop blocks will be such as to normally bring the car to a full stop before the rear block is reached, the block being adapted to stop the car in case it is moving faster than normally or in case the friction is not sufficient to stop it prior to this point.

The present device is comparatively light in weight and yet is strong enough to withstand the hard usage which it necessarily receives. The blocks are fastened under the ball of the rail and have inclined faces which take up the shock from the shoe. The tendency is to wedge the blocks against the

ball of the rail, thus relieving the bolts from the shearing action of a straight blow. The parts of course may be made relatively light as the car is not to be stopped at once, but is gradually slowed down by the friction between the shoe, the channel iron and the rail, before the shoe contacts the stop block. The stop is automatically returned to its normal receiving position and needs no attention while in use, as it is only necessary to install it by slipping it upon the rail where it is to be used. The stop blocks may be readily attached by merely drilling holes in the rail. Thus a very compact inexpensive bumper or stop is obtained.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a car stop, the combination of two stop blocks attached to the rail, a channel iron slidably mounted on said rail between said blocks, a shoe slidably mounted on said channel iron and adapted to receive a car wheel, said shoe being adapted to slide in either direction with the car wheel and engaging with said stop blocks to limit its movement.

2. In a car stop, the combination of two stop blocks attached to the rail, a channel iron slidably mounted on said rail between said blocks, said channel iron having raised ends, a shoe adapted to receive a car wheel and being slidably mounted on said channel iron, said shoe being adapted to move with the car wheel in either direction, and means on said shoe adapted to engage with said stop blocks to limit movement of said shoe in either direction.

3. In a car stop, the combination of two stop blocks attached to the rail, a channel iron slidably mounted on said rail between said blocks, said channel iron having raised ends, a shoe adapted to receive a car wheel and being slidably mounted on said channel iron, said shoe being adapted to engage with the raised ends of said channel to move said channel iron with said shoe, said shoe being also adapted to move with said car wheel in either direction, legs on said shoe engaging under the ball of the rail and adapted to engage with said stop blocks to limit movement of said shoe in either direction.

4. In a car stop, the combination of two stop blocks attached to the rail, a channel iron slidably mounted on said rail between said blocks, said channel iron having raised ends, a shoe adapted to receive a car wheel and being slidably mounted on said channel iron, said shoe being adapted to slide on said chan-

- nel iron and contact one of the raised ends thereof and then move with said channel iron, legs on said shoe adapted to engage with said stops to limit movement of said shoe in either direction, said shoe being adapted to return with the car wheel until engagement with the forward stop.
5. In a car stop, the combination of two stop blocks attached to the rail, a channel iron slidably mounted on said rail between said stops, a shoe slidably mounted on said channel iron and adapted to receive the wheels of a car truck, said shoe being adapted to slide in either direction with the car truck and engaging said stop blocks to limit its movement.
10. In a car stop, the combination of two stop blocks attached to the rail, a channel

iron having raised ends slidably mounted on said rail between said blocks and being 20 of sufficient length to receive a car, a shoe adapted to receive the wheels of a car truck and being slidably mounted on said channel, said shoe being adapted to move along said channel and contact said raised ends of said 25 channel and then move with said channel iron, and legs on said shoe adapted to engage with said stops to limit movement in either direction, said shoe being adapted to return with said car truck upon removal of 30 the car until engagement with said forward stop.

Signed by me, this 6th day of October, 1919.

JAMES U. DUFFY.
